US00D671304S

(12) **United States Design Patent**
Lacorazza et al.

(10) **Patent No.:** **US D671,304 S**
(45) **Date of Patent:** **** Nov. 27, 2012**

(54) **SHOE SOLE**

(75) Inventors: **David Lacorazza**, Norwell, MA (US); **Michael Andrews**, East Falmouth, MA (US); **Brian Christensen**, Centerville, MA (US); **William McInnis**, Westwood, MA (US); **Paul E. Litchfield**, Westboro, MA (US); **Brian Rinella**, Quincy, MA (US)

(73) Assignee: **Reebok International Limited**, London (GB)

(**) Term: **14 Years**

(21) Appl. No.: **29/344,359**

(22) Filed: **Sep. 28, 2009**

(51) **LOC (9) Cl.** 02-04

(52) **U.S. Cl.** **D2/954**; D2/951; D2/955

(58) **Field of Classification Search** ..... D2/902, D2/906, 908, 916, 918, 925, 946, 947, 951-962, D2/977; 36/3 B, 22 R, 24.5, 25 R, 28, 32 R, 36/34 R, 59 C, 67 A, 103

See application file for complete search history.

(57) **CLAIM**

The ornamental design for a shoe sole, as shown and described.

DESCRIPTION

FIG. 1 is a bottom view of a shoe sole showing our new design;

FIG. 2 is a perspective view thereof;

FIG. 3 is a left side view thereof; and,

FIG. 4 is a right side view thereof.

The broken lines in the Figures show environment for illustrative purposes only and forms no part of the claimed design.
